[57] CLAIM

The ornamental design for a calculator button pusher, as shown and described.

DESCRIPTION

FIG. 1 is a front elevational view of the calculator button pusher showing my new design, all other elevations being identical thereto;

FIG. 2 is a rear elevational view thereof;

FIG. 3 is a bottom plan view thereof;

FIG. 4 is a top plan view thereof;

FIG. 5 is a side elevational view thereof; and

FIG. 6 is a opposite side elevational view thereof.
